UNITED STATES PATENT OFFICE.

PER JOHAN HEDLUND, OF JÄRLA, STOCKHOLM, SWEDEN.

ELASTIC-FLUID TURBINE.

940,874.

Specification of Letters Patent. Patented Nov. 23, 1909.

Application filed December 3, 1907. Serial No. 404,917.

To all whom it may concern:

Be it known that I, PER JOHAN HEDLUND, engineer, subject of the King of Sweden, residing at Järla, Stockholm, Sweden, have 5 invented new and useful Improvements in Elastic-Fluid Turbines, of which the following is a specification.

My invention relates to improvements in elastic fluid turbines, such as steam turbines, 10 and particularly to that class thereof comprising a plurality of rows of blades or buckets mounted upon a single drum or rotor; and my invention consists in a novel construction of blade holding element, whereby 15 by the introduction and removal of individual blades is made very easy, and whereby the sockets for receiving and holding said blades are easily formed.

The objects of my invention are, to improve 20 the construction of elastic fluid turbines of the type comprising a plurality of rows of blades or buckets mounted on the same blade holding element, to facilitate the insertion and removal of individual buckets, 25 to hold the buckets in place securely, to facilitate the formation of the bucket-holding sockets, and to permit the construction of a drum or rotor having a number of bucket rings made in one piece with the 30 drum and all of about the same diameter and provided with means for inserting and removing the buckets, individually, and directly, from the sides of said rings.

I will now proceed to describe my invention 35 with reference to the accompanying drawings, illustrating one embodiment thereof, and the method of forming the sockets in the bucket rings, and will then point out the novel features in claims.

40 In said drawings: Figure 1 shows a longitudinal section of a portion of a turbine drum or rotor, and Fig. 2 a transverse section thereof. Fig. 3 illustrates the method of cutting the blade-receiving sockets in the 45 ribs or flanges of the drum or rotor, showing a side view of cutting means, and showing an end view of a portion of a rotor in which sockets are being cut, and Fig. 4 shows an end view of the same parts. Figs. 50 5, 6 and 7 show broaching cutters which may be used in forming the sockets, Figs. 5 and 6 showing respectively a side view and a top view of an alternative form of cutter and Fig. 7 showing a top view of the form 55 of cutter shown in Figs. 3 and 4.

Referring first to Figs. 1 and 2, numeral

1 designates the blade holding member, in this case a drum rotor, and 2 the turbine shaft on which drum 1 is mounted. Said drum is provided with integral flanges or 60 ribs 3, in which are formed sockets 4 for the reception of the bases of buckets 5 of suitable construction. These sockets are of inverted T-shape, as shown, and the buckets are provided with shanks 7 and corresponding T-heads 8 adapted to enter said sockets and be held thereby against centrifugal force, during the rotation of the drum. But I do not limit myself to this particular shape of socket and blade shank and head, but 70 may use any suitable shape permitting the introduction of the blades individually from the side and securely holding the blades against the influence of centrifugal force. The blades are provided with roofs 6, as 75 shown. The sockets 4 of the several ribs are in line, and may be formed readily by means such as indicated in Figs. 3-7 inclusive, comprising a carriage 9 mounted to be moved along a bed 11 by means of a feed 80 screw 10, said carriage provided with a rotary cutter-shaft 12 mounted in suitable bearings with its axis in a plane at right angles to that of shaft 10, and carrying a rotary cutter 13 adapted to cut in the ribs 3 of the 85 drum slots correspondingly to the narrow portions of the sockets 4, but of substantially the full depth of the sockets. Upon the carriage 9 are also mounted, at suitable distances to one side of the rotary cutter 13, 90 other enlarging or broaching cutters 14, 15 and 16, adapted to form the enlargement at the base of each socket 4 by a plurality of successive operations. As indicated, the drum 1 is mounted above the carriage 9, 95 with its axis parallel to shaft 10, the cutters 14, 15 and 16 being so shaped and positioned that they are coincident with equidistant radii of the drum.

In the operation of forming the sockets, 100 the drum 1 is put in place, and, the cutters 14, 15 and 16 having been removed, the cutter 13 is run the length of the drum, by means of the carriage 9 and shaft 10, and is rotated, thereby cutting a slot or kerf in 105 each rib 3 of the drum. The carriage and cutter 13 are then moved back, the first enlarging cutter, 14, is put in place, the drum 1 is rotated a distance corresponding to the distance between two sockets, and the carriage 9 and cutters 13 and 14 are then run 110 the length of the drum again, the cutter 13

cutting a new slot in each rib and the cutter 14 enlarging, at its base, the slot first cut. The operations are then repeated, a further cutter, 15, being applied, and then, during 5 a further traverse of the carriage, the cutter 16 being applied. In this way, by means of the rotary cutter 13 and a suitable number of enlarging cutters, the slots and sockets in the ribs 3 may be formed easily, quickly, 10 and at little expense.

Instead of using a plurality of enlarging tools, as indicated in Figs. 3, 4 and 7, I may use a single tool, having a plurality of cutting portions 19, 20 and 21, of progressively 15 greater size, as illustrated in Figs. 5 and 6.

In Fig. 7, 22 designates the cutting edge of the tool.

Any suitable means may be employed for driving the shaft 12; I have indicated for 20 the purpose a screw 17 and a worm-wheel 18.

It will be noted that when buckets are held as described in sockets formed as described in ribs which are integral with the drum, they are held very firmly and securely, yet they may be inserted very readily and may be removed as readily, and it is not necessary to remove a number of buckets to remove a particular one, but each may be removed and replaced independently of the 25 others.

What I claim is:—

1. A blade-carrying member for elastic fluid turbines adapted for holding a plurality of rows of buckets, said member provided with a plurality of integral circumferential ribs, each projecting beyond the main surface of the member, and each provided with a plurality of sockets, separate from one another, for receiving the bases 35 of individual buckets, each such recess open 40

at the side to receive its bucket from the side, whereby all of said buckets may be inserted from the sides of the ribs, each directly into its corresponding recess.

2. A rotor for elastic fluid turbines adapted for holding a plurality of rows of buckets, said rotor comprising a drum provided with a plurality of integral circumferential ribs, each projecting beyond the main surface of the drum, and each provided with a plurality of sockets, separate from one another, and each open at the side to receive a corresponding bucket, and a plurality of rows of buckets, each bucket having a base received individually in a corresponding 50 socket.

3. A rotor for elastic fluid turbines adapted for holding a plurality of rows of buckets, said rotor comprising a drum provided with a plurality of integral circumferential ribs, 55 each projecting beyond the main surface of the drum, and each provided with a plurality of sockets, separate from one another, and each open at the side and enlarged at the bottom, corresponding sockets of different 60 ribs being in line and adapted to be formed by means moving with respect of the drum.

4. A turbine drum with a plurality of bucket rings made in one piece with the drum, each ring provided with recesses opening at each side of the ring and engaging 65 buckets, each inserted from the side directly into its corresponding recess.

In testimony whereof I have signed my name to this specification in the presence of 70 two subscribing witnesses.

PER JOHAN HEDLUND.
